(57) **CLAIM**

The ornamental design for ear cushion for earphone assembly, as shown and described.

DESCRIPTION

FIG. 1 is a perspective view of an ear cushion for earphone assembly in accordance with the new design.

FIG. 2 is a perspective view of the ear cushion of FIG. 1, depicting the ear cushion disposed on an of earphone (in phantom).

FIG. 3 is a first elevation view of the ear cushion of FIG. 1, depicting a first planar side in which the terminal end of the ear cushion curved to the right, as viewed.

FIG. 4 is a second elevation view of the ear cushion of FIG. 1, depicting a second planar side in which the terminal end of the ear cushion curved to the left, as viewed.

FIG. 5 is a first side view of the ear cushion of FIG. 1, depicting a concave side of the ear cushion.

FIG. 6 is an opposite side of FIG. 5.

FIG. 7 is a top view of the ear cushion of FIG. 1; and,

FIG. 8 is a bottom view of the ear cushion of FIG. 1.

The dashed lines depict environmental aspects and form no part of the claimed design.
